US0D1018806S

(12) **United States Design Patent** (10) **Patent No.:** **US D1,018,806 S**
(45) **Date of Patent:** **** Mar. 19, 2024**

(54) **WATER PAN**

(71) Applicant: **Yazhen Zhang**, Jinhua (CN)

(72) Inventor: **Yazhen Zhang**, Jinhua (CN)

(**) Term: **15 Years**

(21) Appl. No.: **29/895,837**

(22) Filed: **Jun. 27, 2023**

(51) **LOC (14) Cl.** **23-01**

(52) **U.S. Cl.**

USPC **D23/268**

(58) **Field of Classification Search**

USPC **D23/267-268**

CPC **Y10T 137/87901; Y10T 137/877; E03F 5/06**

Primary Examiner — Robert A Delehanty

(74) *Attorney, Agent, or Firm* — Jose Cherson Weissbrot

(57) **CLAIM**

The ornamental design for a water pan, as shown and described.

DESCRIPTION

FIG. 1 is a top perspective view of a water pan, showing my new design;

FIG. 2 is a bottom perspective view thereof;

FIG. 3 is a front elevational view thereof, the rear elevational view is identical;

FIG. 4 is a left side view thereof, the right side view is identical;

FIG. 5 is a top plan view thereof; and,

FIG. 6 is a bottom plan view thereof.

The broken lines in the figures are for the purposes of illustrating portions of the water pan, which form no part of the claimed design.

1 Claim, 5 Drawing Sheets
